UNITED STATES PATENT OFFICE.

FREDERICK J. RAPPOLD, OF ERIE, PENNSYLVANIA.

HOOK AND EYE.

1,261,165.

Specification of Letters Patent. Patented Apr. 2, 1918.

Application filed December 19, 1916, Serial No. 137,871. Renewed February 25, 1918. Serial No. 219,155.

To all whom it may concern:

Be it known that I, FREDERICK J. RAPPOLD, a citizen of the United States, and resident of Erie, in the county of Erie and

5 State of Pennsylvania, have invented new and useful Improvements in Hooks and Eyes, of which the following is a specification.

My invention relates to new and useful 10 Improvements in garment fasteners, and more particularly to a fastener commonly known as hook and eye.

The principal object of my invention is to provide a hook and eye fastener which is 15 especially adapted for heavy garments, such as fur coats and fur collars, also capes, scarfs, coats and the like, but may be used upon other garments equally as well.

A further object of the present invention 20 is to provide a hook and eye fastener, each of which members being formed from a length of wire, and which when engaged will be positively retained against accidental disengagement.

25 Another object of the invention is to provide a hook and eye fastener which is simple in construction, and is constructed in few operations and which may be placed on the market at a comparatively low cost.

30 The above and other objects and advantages of the present invention will be hereinafter set forth and claimed and illustrated in the accompanying drawings, in which:—

35 Figure 1 is a perspective view of an eye member constructed in accordance with my invention,

Fig. 2 is a like view of the hook member,

Fig. 3 is a side elevation of the hook and 40 eye members engaged,

Fig. 4 is a top elevation showing the members engaged,

Fig. 5 is a view taken on line $\alpha-\alpha$ of Fig. 4, and showing the hook and eye members being engaged,

Fig. 6 is a like view showing the members being disengaged.

Fig. 7 is a view of a modified form of eye,

50 Fig. 8 is a view of a modified form of the unfinished hook, and Fig. 9 is a view showing the finished shape of the modified form of hook.

Like characters of reference indicate like 55 parts in all of the views.

For the purpose of distinguishing the hook and eye members, the same will be designated by the letters A and B respectively.

This hook member A is formed from a 60 length of wire indicated, as a whole, by the numeral 5. This length of wire is bent to afford a pair of divergent legs 6, the ends of which are looped upon themselves to provide attaching eyes 7, which are adapted to 65 be stitched or otherwise secured to the garment.

The forward portions of these legs are 70 extended in parallelism and then reversely bent as at 8 and extended in parallelism with the parallel portions of the legs 6 to provide a hook 9. The forward ends of this hook 9 are reversely bent as at 10 to provide a substantially U-shaped portion or guide 11.

The eye member B is also constructed 75 from a length of wire, this being indicated by the numeral 12. This length of wire 12 is bent to a substantially V-shaped configuration. One end of this V-shaped member is bent to provide an attaching eye 13, while 80 its opposite end is likewise bent to provide an attaching eye 14.

From the eye 14, this end of the wire is 85 extended longitudinally and between the divergent bars of the V-shaped member to provide a tongue or keeper 15.

The manner of engaging and disengaging the hook and eye members is substantially as follows:—

As clearly illustrated in Fig. 5, the eye 90 member B is engaged with the hook member A at the forward end thereof so that the tongue 15 will be in alinement with the U-shaped guide 11 and free to pass therein. The eye member B is then moved longitudinally until it engages the bend 8 of the hook 10. When it is desired to disengage the members, the eye member B is simply moved to the position shown in Fig. 6 which will allow the tongue or keeper 15 to engage 95 the hook at the point where the guide 11 is formed, which will allow the members to 100 be disengaged.

It will be seen that when the hook and eye are engaged should there be any longitudinal shifting of the members, it will 105 be impossible for them to become accidentally disengaged.

The modified form of hook and eye shown in Figs. 7, 8 and 9 is an improvement 110

over the structure shown in my prior patent on hook and eye numbered 564,255 issued July 21, 1896.

Referring to these Figs. Nos. 7, 8 and 9, this form of hook 17 and eye 18 are preferably stamped from sheet metal and in the process of making the hook is bent on the line 9—9 as shown in Fig. 8.

Apertures 19 are used for fastening the devices to various forms of garments and other members (not shown).

A tongue member 20 is provided in the eye 18 and into the spaces 21 on each side of the tongue 20 the hook end 22 is adapted to be inserted. This form of hook and eye has been found to be very satisfactory and successful. Each member is cheaply and easily made, and the structure has many advantages over the hooks and eyes now on the market.

While the form described I now consider to be the preferred embodiment of the invention, I am desirous of having it known that

the invention may be modified in many different respects that may fairly fall within the scope of the appended claim.

What is claimed is:

The combination with an eye having a resilient locking tongue which normally lies in the plane of the eye, of a hook formed from a length of wire bent to form a substantially U-shaped member, the U-shaped member being bent at its forward end and extended reversely to provide a hook which lies parallel to the major portion of the U-shaped member, the extremity of the hook being bent inwardly to afford a U-shaped guide which lies in the plane of the hook and is adapted to receive the locking tongue of the eye and spring the same out of the plane of the eye upon the engagement of the eye with the hook, the vertex of the U-shaped guide being adapted to spring the tongue out of the plane of the eye upon the disengagement of the hook and eye.

FREDERICK J. RAPPOLD.
